UNITED STATES PATENT OFFICE.

DAVID M. CROOKER, OF PORT HURON, MICHIGAN.

LIGHT-SIGNAL.

1,189,065.

Specification of Letters Patent. Patented June 27, 1916.

Application filed December 2, 1913. Serial No. 804,137.

To all whom it may concern:

Be it known that I, DAVID M. CROOKER, a full citizen of the United States, residing at Port Huron, in the county of St. Clair and State of Michigan, have invented new and useful Improvements in Light-Signals, of which the following is a specification.

The invention relates to an improvement in light signals, particularly for nautical use and constructed for flashing simultaneously with the operation of the usual audible signal, as a whistle blast.

The main object of the present invention is the provision of a visual signal in the form of a flashing light which is automatically actuated in the sounding of the whistle, so that the alarms are simultaneously given in order to insure an effective signaling at night or in foggy weather.

20 The invention in the preferred form of details will be described in the following specification, reference being had particularly to the accompanying drawings, in which:—

Figure 1 is a broken elevation, partly in section, illustrating the application of the improvement. Fig. 2 is an enlarged broken sectional view showing the signal.

In the accompanying drawings, 1 represents generally the vessel having the usual whistle 2 supplied with steam or other power through a pipe 3, the valve of the whistle being operated by a lever 4, spring actuated in one direction through the medium of the spring 5. The lever 4 is actuated through a pull cord 6 extending into the engine room 7 or through a pull cord 8 connected to the foot lever 9 in the pilot house 10, whereby the whistle may be sounded from either position.

40 Rising from the deck or other convenient part of the vessel preferably adjacent the whistle is a mast 11 carrying one or more signals 12. The signals, if more than one is used, are in series circuit with the source of energy, as battery 13, arranged in the engineroom through conductors 14 and 15 leading from the battery to the signal and to the switch 16 and the conductor 17 leading from the switch to the signal. The switch 50 includes a fixed member 18 and a movable

member 19 which latter is in the form of a lever connected through the medium of a rod 20 with the whistle lever 4, the arrangement of the parts being such that when the lever 4 is operated to sound the whistle the 55 circuit including the conductors 14, 15 and 17 is closed to energize the signal. The signal and source of energy are also in circuit with the hand switch 20^a arranged in the pilot house 10, conductors 21 and 22 leading 60 from the switch to the battery and signal respectively, the conductor 14 of the first mentioned circuit serving as remaining conductor of the last mentioned circuit. The lever 9 for operating the whistle in the pilot 65 house also controls the switch 23 from which conductors 24 and 25 extend through the conductors 21 and 14 of the other circuits.

From the above construction, it will be obvious that of each operation of the lever 70 4 to sound the whistle either by means of the cord 6 of foot lever 9 the light signal will be correspondingly flashed, remaining energized during continuation of the audible alarm and that in the event of the failure of 75 the whistle to operate from any cause, the visual alarm will be actuated through the medium of the switch 20^a.

By providing the switch 23 and the switch 18 in the independent circuits connected with the visual signal and operating the said switches by means for actuating the audible signal, it is at once apparent that should either of the flexible members 6 and 8 stretch or break, thus disconnecting the 80 operating means for the switch 18 and the audible signal, the visual signal could still be operated by depressing the foot lever 9, or grasping the rod 20 and exerting a downward pull.

90 In Fig. 2 I have shown the visual alarm in the form of a glass sphere within which are arranged low and high candle power incandescent lamps 27 in series.

95 What is claimed is:—

A device of the kind described comprising a plurality of lamps, an audible signal comprising a whistle having a valve, a spring operated lever controlling the valve, a battery circuit, a pull cord for operating said 100

lever, a circuit closing switch connected with the said lever, means whereby said switch operates in unison with said lever to close said circuit, said switch being operated by said lever, said lamps and switch being included in said circuit, a foot-pressed switch, contacts engaged by said foot-pressed switch and included in said circuit, to operate said

lamp, and a cable connecting said foot-pressed switch to said lever.

In testimony whereof I affix my signature in presence of two witnesses.

DAVID M. CROOKER.
